UNITED STATES PATENT OFFICE.

GUY MARDOCK, OF ILLINOIS CITY, ILLINOIS.

UMBRELLA-HOLDER.

1,133,989.

Specification of Letters Patent. Patented Mar. 30, 1915.

Application filed December 16, 1913. Serial No. 807,113.

To all whom it may concern:

Be it known that I, GUY MARDOCK, a citizen of the United States, residing at Illinois City, in the county of Rock Island and 5 State of Illinois, have invented new and useful improvements in Umbrella-Holders, of which the following is a specification.

This invention relates to umbrella holders, and particularly to a holder designed 10 for use upon the frame of a riding plow and it has for its object the provision of a holder of this character which may be readily applied to the frame in advance of the driver's seat and provided with means which will 15 be adjustable to secure the holder in place upon the frame and to also confine the umbrella in a supported position.

Another object of the invention is the provision of an umbrella holder which will 20 consist of a socket member having adjustable portions that are adapted when adjusted to prescribed positions to permit of the convenient application of the stick of the umbrella to the holder or the removal of 25 the same therefrom.

With these and other objects in view, the invention consists of certain novel features of construction, combination and arrangement of parts, as will be hereinafter 30 described and claimed.

In the accompanying drawings:—Figure 1 is a perspective view of a portion of a seat of an agricultural implement, showing the application of the invention thereto; 35 Fig. 2 is a perspective view of the holder; Fig. 3 is a perspective view of the holder, showing the different parts thereof separated from each other; and Fig. 4 is a vertical section through the holder.

40 The holder is one of a design which may be used in connection with a form of riding plow having a frame A, as shown in Fig. 1 and a seat B mounted on the frame in the usual manner. The frame in the present 45 instance has spaced parallel bars and between the bars at a suitable point in advance of the driver's seat B is mounted the holder.

The holder consists of mating socket and 50 clamping sections 1 and 2, the former being respectively provided at its upper and lower ends with lugs 4 and 8, which are disposed directly against similar lugs 5 and 9 respectively formed at the upper and lower 55 ends of the section 2. The said sections 1 and 2 are provided with arcuate inner walls

which together, define a continuous cylindrical passage 3, in which the stick C of the umbrella D herein shown may be extended.

A fastening clip 7 is employed for the dual purpose of retaining the sections in clamped positions about the stick and to also hold the sections properly applied to the plow frame. This clip is provided with a 60 long branch 11 and short angularly disposed branches 6 and 10, the former being extended through suitable passages in the lugs 4 and 5 of the sections 1 and 2, while the branch 10 is extended through the 65 passages formed in the mating lugs 8 and 9. The lugs formed on the sections 1 and 2 are offset sufficiently from the axis of the 70 passage 3 so that the long branch 11 of the clip will be arranged at such an angle that will 75 permit the holder to be supported in a vertical position when disposed between the parallel bars of the frame A. One of the bars is adapted to be passed between the 80 clips and the adjacent section 1 of the holder.

The branches 6 and 10 are threaded at 12 and mounted for adjustments on the threaded portions are clamping nuts 13, which are adapted to be adjusted manually so as to 85 effect a proper application of the holder to the frame and to also move the sections 1 and 2 with relation to each other and into proper clamping engagement with the stick.

Through the construction described it is 90 readily apparent that the holder may be readily connected with or disconnected from any standard form of plow frame; that the stick of the umbrella is free for vertical 95 sliding adjustment when the sections 1 and 2 of the holder are moved slightly away from each other and that when the sections are moved toward each other, the stick will be properly held in the required adjusted 100 position.

From the foregoing description, taken in connection with the accompanying drawings, the construction and operation of the invention will be readily understood without requiring a more extended explanation.

105 Various changes in the form, proportion and the minor details of construction may be resorted to without departing from the principle or sacrificing any of the advantages of this invention as claimed.

I claim:—

110 In combination with a seat supporting bar,

an umbrella holder comprising a pair of matched sections arranged on one side of said bar and having a vertical opening in the opposing sides to receive an umbrella stick, and a U-bolt arranged with its central portion on the opposite side of said bar and with its arms above and below the bar and passed through coincident openings in said matched sections, and nuts screwed 10 on said arms of the U-bolt and clamping

said sections together and on opposite sides of the umbrella stick and also clamping said bar between said U-bolt and one of the said matched sections.

In testimony whereof I affix my signature in presence of two witnesses.

GUY MARDOCK.
